ERWIN E. RADLOFF AND AUGUST W. JANKE, OF MILWAUKEE, WISCONSIN, ASSIGNORS
TO C. B. HENSCHEL MFG. CO., OF MILWAUKEE, WISCONSIN

ATTACHMENT FOR BRONZING MACHINES

Application filed August 25, 1928. Serial No. 302,116.

This invention relates to an attachment for bronzing machines.

In bronzing machines, it is the usual practice to carry the sheets upon a rubber blanket 5 or belt and to operate upon the sheets while they are supported by the belt. It has been found that the sheets tend to stick to the belt and are not freely discharged therefrom, so that they may be received by the sheet receiving means. It is thought that the static electricity generated by operating upon the sheets causes them to adhere to the belt. Various means have been tried, such as stripping fingers, to remove the bronze sheets 10 from the belt, but it has been found that these fingers mar the sheets and injure their appearance.

This invention is designed to provide a very simple and serviceable means for removing or loosening the sheets from the belt without producing any marring whatsoever upon the sheets, thus leaving the sheets in their initial integrity and permitting their ready reception by the sheet receiving means.

More specifically, objects of this invention are to provide a sheet removing means which is operated through the agency of a series of blasts of air directed towards the belt to thus free the oncoming sheets from the belt, 25 so that they may be readily received by the sheet receiving means without touching the sheets during this removal by any mechanism whatsoever.

Embodiments of the invention are shown 30 in the accompanying drawings in which:

Figure 1 is a side elevation with parts broken away showing diagrammatically a bronzing machine;

Figure 2 is an end view of the sheet receiving means and the adjacent portion of the belt, the air pipe being shown in section;

Figure 3 is a view of the belt and air pipe corresponding to a plan view of the structure shown in Figure 1 with, however, the upper 40 rollers removed;

Figure 4 is a view of a modified form of air pump, such view showing the device with the end cap removed;

Figure 5 is a sectional view on the line 50 5-5 of Figure 4.

Referring to the drawings, it will be seen that the bronzing machine is provided with a continuous rubber belt 1 which is usually termed a blanket. This belt receives the sheets and passes them through the casing 2 where they are operated upon by the members 3. The belt 1 extends over the forward and rear rollers 4 and 5, as indicated in dotted lines in Figure 1, and at the discharge end of the belt, a plush roller 6 is positioned 55 immediately above the roller 4. The sheet receiving means comprises an upper and a lower plush roller, indicated by the reference characters 7 and 8.

Immediately adjacent the discharge end of 60 the belt, a transverse air pipe 9 is positioned. This air pipe, it will be seen from Figure 2, is in front of the sheet receiving rollers 6 and 7, and closely adjacent the belt.

The pipe is provided with a multitude of 65 forwardly directed apertures 10 adapted to direct a pulsating blast of air towards the belt to thus dislodge the sheets so that they may be readily received by the rollers 7 and 8.

It has been found that a reciprocating air 70 pump, such as indicated at 11 in Figures 1 and 3, forms an effective means for supplying the pulsating air blast. This pump is directly connected to the pipe 9 without any intermediate storage tank. The intake may be provided with a filtering nozzle or head 12 or any suitable construction. The pump has its piston rod 13 connected in any suitable manner to a source of power, such for example, as by means of the crank 14 and link 15. The 75 crank is driven by means of the pulley 16 which may be belted to any portion of the machine desired. Obviously, other forms of driving the reciprocating pump could be employed without departing from the spirit of 80 this invention.

It has been found that a pneumatic dislodging means, such as disclosed in this invention, operates perfectly and dislodges the 85 sheets in a certain and reliable manner without producing any defacement of the sheets whatsoever.

It is to be noted also that the construction is extremely simple and may be readily ap- 100

plied to existing machines without requiring any alteration of the machine.

It is to be noted further that the dislodging means does not interfere with any other portion of the machine.

5 Referring to Figures 4 and 5, the modified form of air pipe or blower consists of a casting 17 within which an eccentric rotor 18 is mounted. This rotor carries vanes 19 which, 10 in the form shown, are three in number. The vanes are adapted to contact with the inner surface of the cylindrical casing 17 when the rotor is operated, due to centrifugal action. Thus, all springs or other members of this 15 type are wholly avoided, and a very simple sealing action takes place.

The rotor is provided with a projecting shaft 20 which carries a driven pulley 21. The other end of the rotor is provided with 20 a short shaft 22 which is received within the bearing portion or end cap 23. The end cap is provided with inlet and outlet openings 24 and 25 which communicate with annular grooved out portions 26 and 27.

25 The device is so made, and it has been found from actual tests, that a rapid series of blasts of air are produced. The effect is the same as if a reciprocating pump operated at a high speed had been used, and consequently the 30 results enumerated above are also obtained by this device.

The device, it will be noted, is substantially balanced and will not produce vibration or rattling.

35 Although the invention has been described in considerable detail, such description is intended as illustrative rather than limiting as the invention may be variously embodied and as the scope of such invention is to be determined as claimed.

40 We claim:

45 In combination with a plurality of rollers arranged in intimate contact and in opposed pairs with the pairs extending both vertically and horizontally, of a feeding belt passing around one of said rollers and in intimate contact with a vertically opposed roller for receiving sheets thereon, and an air pipe extending longitudinally of the roller around 50 which the belt passes and having a plurality of apertures directed in an upwardly inclined plane toward said belt, and means for directing a pulsating blast of air through said apertures to free the sheets from said belt.

55 In testimony that we claim the foregoing we have hereunto set our hands at Milwaukee, in the county of Milwaukee and State of Wisconsin.
